(No Model.)

J. SULLIVAN.
HUB CLAMP AND WRENCH COMBINED.

No. 430,814.

Patented June 24, 1890.

UNITED STATES PATENT OFFICE.

JOHN SULLIVAN, OF GRAND RAPIDS, MICHIGAN.

HUB-CLAMP AND WRENCH COMBINED.

SPECIFICATION forming part of Letters Patent No. 430,814, dated June 24, 1890.

Application filed November 19, 1889. Serial No. 330,876. (No model.)

To all whom it may concern:

Be it known that I, JOHN SULLIVAN, of Grand Rapids, in the county of Kent and State of Michigan, have invented a new and 5 Improved Hub-Clamp and Wrench Combined, of which the following is a full, clear, and exact description.

My invention relates to an improved means for the simultaneous removal of a spindle- 10 nut and the wheel of a vehicle, and consists in the production of a simple, compact, and convenient implement by the use of which the hub of a vehicle-wheel may be firmly gripped and the wheel, along with the spindle- 15 nut, be expeditiously and readily removed.

To these ends my invention consists in the construction and combination of parts, as hereinafter described, and indicated in the claims.

Reference is to be made to the accompanying drawings, forming a part of this specification, in which similar letters of reference indicate corresponding parts in all the figures.

Figure 1 is a longitudinal section of a 25 wheel-hub mounted on an axle-spindle, with the improved wheel and nut remover in position thereon. Fig. 2 is an enlarged view in perspective of the improved implement. Fig. 3 is a side view of the wrench proper removed 30 from the hub-gripping device, and Fig. 4 is a side view of a detached portion of the implement.

A represents a lever-wrench, the handle portion *a* of which is made of sufficient length 35 for its use. At *A'* the handle is enlarged, producing a head-piece, which is notched on its edge at *b c d* to provide open recesses which can be utilized as wrenches for engagement of bolt-heads or nuts. These open-jaw 40 wrenches, being of different dimensions, afford means for the adjustment of the different-sized nuts and bolts used in the construction of a wheeled vehicle, an open-jaw wrench being also provided at *d'* on the end of the handle.

At a central point in the head *A'* of the wrench *A* a square orifice is formed, into which the shank *e* of the socket-piece *B* is inserted, the shank fitting therein neatly, 45 and, extending outside of the wrench-head, is adjustably secured in the aperture by a spring-clip *e'*, which is bent from a piece of

elastic wire, and engages the parallel grooves *e*, that are formed in the shank-body near its free end, the spring resting in a groove *a'* 55 formed in the face of the head *A'*.

The socket-piece *B* is designed to receive a spindle-nut *f* in its square or hexagonal recessed body, as shown in Fig. 1, and as it is made removable from the wrench *A* there 60 may be a set of different-sized socket-pieces provided for the removal of various-sized spindle-nuts on different vehicles, and a set-screw *n* is preferably inserted in the side wall of the sockets *B*, (see Fig. 4,) so as to afford 65 means for engaging nuts which will not fit the sockets.

It is of advantage to remove the wheel of a vehicle and the nut of the spindle at one operation and hold the parts intact, so that the 70 handling of the nut, which is smeared with tar or grease, may be avoided when the wheel and nut are replaced upon the spindle. To effect this desideratum a clamping device is provided, which is combined with the wrench 75 *A* and socket-piece *B*, as will be explained. The yoke-bar *g* is proportioned to the width between the notches *b d* in the wrench-head *A'*, so that the integral limb *h* and hinged limb *h'* secured to its ends will lie in said 80 notches, as shown in Figs. 1 and 2. These limbs *h h'* are suitably curved and extend between the spokes of a wheel, to engage the hub-band *i* on the inner end of the hub *k* with the hooks *h*, formed on the terminal 85 ends of the limbs *h h'*, thus retaining the limbs in contact therewith. A set-screw bolt *m* is inserted in a central tapped hole produced in the yoke-plate *g*, which screw-bolt engages a seat or depression formed in the end of the 90 shank *e*, and by its longitudinal adjustment secures all parts of the device upon a wheel and its spindle-nut, so that a revolution of the handle-piece *a* of the wrench *A* will remove the nut and wheel together and retain 95 the nut properly aligned to be restored to place on the spindle when this is desired.

Having thus fully described my invention, I claim as new, and desire to secure by Letters Patent—

1. The combination, with a wrench having a central aperture in its head and with opposite notches in the edge of the same, of a socket-piece secured in the aperture of the

head, a yoke-bar provided with a rigid and pivoted limb, each having a hook-shaped end and resting in the notches of the wrench-head, and a set-screw passing through the 5 yoke-piece and bearing against the socket-piece, substantially as described.

2. The combination, with the wrench A, provided with the head A', having a central aperture and provided with the notches *b d*, 10 of the socket-piece B, provided with the shank *e*, detachably secured in the aperture of the said

head, the yoke bar or piece *g*, provided with a rigid limb *h* and a pivoted limb *h'*, each having a hook-shaped end and resting in the notches of the wrench-head, and the set-screw 15 *m*, passing through the yoke-piece and bearing against the shank of the socket-piece, substantially as herein shown and described.

JOHN SULLIVAN.
